UNITED STATES PATENT OFFICE

2,615,683

DRILLING APPARATUS

Robert Anthony McCallum, Michigan City, Ind.,
assignor to Joy Manufacturing Company, a cor-
poration of Pennsylvania

Application October 23, 1944, Serial No. 559,982

9 Claims. (Cl. 255—47)

1

This invention relates to drilling apparatus and more particularly to an improved feeding mechanism for the drilling implement of a drilling apparatus of the high speed rotary type especially designed for use in drilling blast holes in rock or the like.

An object of the present invention is to provide an improved drilling apparatus of the rotary blast hole type. Another object is to provide an improved feeding mechanism for the drilling implement of a rotary type drilling apparatus. Yet another object is to provide an improved feeding mechanism embodying relatively rotatable, mechanically interengaged feeding elements arranged in a novel manner. A further object is to provide an improved feeding mechanism wherein one of the feeding elements is arranged coaxially with and extends into a motor element of the drilling motor. A still further object is to provide an improved feeding mechanism embodying a stationary feed screw arranged coaxially with and extending into a motor element of the drilling motor and a cooperating rotary feed nut driven by and movable with the drilling motor. Yet another object is to provide an improved feeding mechanism having improved variable speed driving means therefor. Still another object is to provide in a drilling apparatus of the sort referred to an improved general arrangement of parts, and especially an improved relationship between the feeding mechanism and the other elements. These and other objects and advantages of the invention will, however, hereinafter more fully appear.

In the accompanying drawings there are shown for purposes of illustration two forms which the invention may assume in practice.

In these drawings:

Fig. 1 is a side elevational view of a drilling apparatus constructed in accordance with an illustrative embodiment of the invention.

Fig. 2 is an enlarged longitudinal vertical section taken through the drilling apparatus shown in Fig. 1, with parts broken away to facilitate illustration.

Fig. 3 is an enlarged cross-sectional view taken substantially on line 3—3 of Fig. 2.

Fig. 4 is an enlarged cross-sectional view taken substantially on line 4—4 of Fig. 2.

Fig. 5 is an enlarged cross-sectional view taken substantially on line 5—5 of Fig. 2.

Fig. 6 is an enlarged detail sectional view taken on line 6—6 of Fig. 5.

Fig. 7 is an enlarged sectional view taken on

2

the plane of Fig. 2, illustrating another embodiment of the invention.

Fig. 8 is a cross-sectional view taken substantially on line 8—8 of Fig. 7.

Fig. 9 is a detail sectional view taken on line 9—9 of Fig. 7.

In both illustrative embodiments of the invention, there is shown an improved rotary high speed rock drilling apparatus of the blast hole type embodying a motor 1 for rotating a drilling implement 2, herein preferably a diamond impregnated bit, and an improved feeding mechanism 3 for moving the drilling motor back and forth along a guide 4. While the invention is shown embodied in a drilling apparatus of the rotary type, evidently various features of the invention may be associated with drilling apparatus of other types.

In the illustrative embodiment of the invention shown in Figs. 1 to 6 inclusive, the drilling motor 1 is herein of the rotary type and is preferably a high speed electric motor of the totally enclosed type having a stator casing 5 provided with front and rear heads 6 and 7. The motor heads are attached to the motor casing by tie-bolts 8. The motor has a usual field 9 and an armature rotor 10, the latter being fixed to a tubular shaft 11 journaled in bearings suitably supported in the motor heads. Attached by a coupling 12 to the reduced threaded forward end of the tubular motor shaft 11 is a drill rod 13 which carries the drilling implement 2. Mounted on the rotary coupling 12 is a stuffing box 14 through which cleansing fluid may be supplied from a hose connection 15 through passages 16 to the drill rod 13 to clear away the cuttings from the drilling implement during the drilling operation in a well known manner. The rear motor head 7 has lateral guides 17, 17 slidably received in longitudinal guideways 18 of the guide 4, and the latter has a usual swivel plate 19' adapted to be clamped in a usual saddle mounting of a drill support.

Now referring to the improved feeding mechanism 3, shown in Figs. 1 to 6 inclusive, it will be noted that arranged coaxially with the armature rotor 10 of the motor is a feed screw 19, the latter being rigidly secured as by a nut 20 threaded on the reduced rearward extremity 21 of the feed screw, to an upstanding support 22 secured as by bolts 23 to the rear end of the guide 4. When the drilling motor is in its retracted position on the guide, the stationary feed screw 19 is telescopically arranged within the tubular shaft 11 of the motor in the manner shown in Fig. 2. The

rear motor head 7 is formed with a chamber 24 closed by a rear cover plate 25 detachably secured as by screws 26 to the motor head. Journaled within a bearing 27 supported by the cover plate 25, and arranged in the rear head chamber 24 is a rotatable feed nut 28 engaging the threads of the stationary feed screw 19. If desired the forward end of the feed nut 28 may be journaled on a bearing on the rearward portion of the tubular motor shaft, and thrust bearings may be provided at the opposite ends of the feed nut for transmitting the feeding pressures to the drilling motor. A similar bearing mounting for the feed nut is disclosed hereinafter in the modified embodiment of the invention. Also arranged in the head chamber 24 is a variable speed reduction gearing generally designated 29 operatively connected between the motor rotor 10 and the feed nut 28 for rotating the latter at variable speeds. The reduction gearing 29 is preferably of the frictionally controlled planetary type and, in this instance, comprises a rotatable carrier 30 having its hub 31 keyed at 32 to the rear end of the motor shaft 11. Secured at 33 to the rotary carrier 30 are stub shafts 34 on which planet 25 gears 35, herein three, are journaled, and these planet gears mesh with a sun gear 36 secured to the rotatable feed nut 28. Planet gears 37 respectively formed integral with and of smaller diameter than the gears 35 mesh with a reaction gear 38, the latter preferably formed integral with a friction drum 39 suitably journaled on the feed nut 28. A suitable friction band 40 is adapted to engage the outer periphery of the friction drum 39 to hold the latter from rotatable movement or to allow the friction drum to slip therein for varying the speed of the planetary reduction gearing and for preventing overload of the parts therein and driven thereby in an obvious manner. The friction band 40 is at one end pivotally connected at 41 (Figs. 5 and 6) to a bracket 42 attached as by a bolt 43 to the rear casing head, and the other end of the friction band is engaged by the head 44 of a bolt 45. This bolt passes through an opening in the pivoted end of the band and extends outwardly through an opening 46 in the casing head and has a threaded portion 47 engaged by a hand nut 48. A spring 49 interposed between the ends of the friction band and surrounding the bolt urges the ends of the band apart toward released position. By adjustment of this hand nut, the friction band may be tightened or loosened as desired. When the friction band 40 is loosened, the reaction gear 38 is free to rotate, and, as a result, during running of the motor, the planet gears 35 may freely revolve around the sun gear 36 while the feed nut 28 remains stationary. When the friction drum 39 is held against rotation by the friction band 40 and the reaction gear 38 is held against rotation, the carrier 30, as it is driven by the motor, effects clockwise (locking forwardly) planet motion of the planetary gears 37 about the non-rotating reaction gear 38, and, as a result, the planet gears 35 revolve and drive the sun gear 36 to effect rotation of the feed nut 28 at a slow speed to effect forward feed. As the feed nut is rotated, the drilling motor 1 is fed forwardly along the guideways of the guide 4. By adjusting the friction band the friction drum may be allowed to slip therein for varying the speed of the planetary gear reduction and for preventing overload of the feed. To effect reversal of the feed, the drilling motor may be reversible or, if desired, a conventional planetary reverse gearing may be em- 70

bodied in the planetary reduction gearing 29 so that reverse drive of the feed nut may be effected without reversing the motor. Since a reversible planetary gearing is well known further disclosure thereof herein is considered unnecessary. 5 In the modified embodiment of the invention shown in Figs. 7 to 9 inclusive, the drilling apparatus is generally similar to that described above, but, in this instance, there is provided a frictionally controlled planetary reduction gearing, generally designated 50, embodying a selective transmission, whereby the feed nut may be selectively driven at different predetermined speeds and under friction control at any speed. 10 In this embodiment, a rotatable feed nut 28' engages the threads of the stationary feed screw 19 and is journaled in the rear head casing. Secured to the rear end of the tubular motor shaft 11 is a flange 51 to which is secured, as by screws 20 52, a rotatable carrier 53, the latter in turn being freely rotatable on bearings 54. Supported by the spaced end portions of the carrier 53 are shafts 55 on which planet gear units 56 are journaled. These planet gear units are three in number and are identical in construction and each comprises gears 57, 58, 59, 60 and 61 rigidly secured together as by rivets 62. The gears 57, 58, 59 and 60 are of different diameters, and each provides a different reduction, and the rear end 30 gears 61 of the planet gear units mesh with an internal gear 63 formed on a rotatable member 64 secured to the feed nut 28'. The front bearing 54 is supported in the hub of the flange 51 while the rear bearing 54 is supported by the hub of the rotatable member 64, and the hub of the latter is journaled in a bearing supported by the end plate 25' of the rear casing head. These bearings also support the rotatable feed nut 28' as shown. The planet gears 57, 58, 59 and 60 respectively mesh with internal gears 65, 66, 67 and 68 rotatably supported within the rear casing head. These internal gears may be rotatably mounted in various known manners and, in this construction, the opposite end internal gears 65 and 68 are journaled at 69 and 70 on the rotatable carrier 53 and the rotatable member 64 respectively, and the intermediate internal gears 66 and 67 are rotatably mounted at 71 and 72 on the gears 65 and 68 and also at 73 one on the other in the manner shown. These internal gears 65, 66, 67 and 68 are formed integral with rotatable friction drums with which friction bands 74, 75, 76 and 77 respectively cooperate. Each of these friction bands is pivotally connected at one end at 78 (see Fig. 8) to a bracket 79 secured to the rear head casing, and the other end of each band is pivotally connected at 80 to a bolt 81. The bolt extends through an opening 82 in the pivoted end of the band and has a head 83 engaging the outer side of the pivoted end of the band. Interposed between the ends of the friction bands and surrounding the bolts 81 are springs 84 for urging the ends of the bands apart toward released position. For selectively tightening the friction bands, there is provided a shiftable cam member 85 secured to a slidable operating shaft 86 guided in a bore 87 in the end plate 25' of the rear head casing. The shaft has a handle 88 at its outer end whereby the same may be moved axially in its bore to bring the cam member 85 opposite the desired one of the friction bands so that, upon rotation of the cam member, the ends of the friction band may be drawn together against the compression of the 65 spring to hold the friction drum stationary. A 75

spring pressed detent 89 is engageable with grooves 90 on the shaft 86 for holding the cam member in its different positions of adjustment. When the friction band 77, shown in Fig. 9, is tightened by the cam member 85, the internal gear 68 is held against rotation, and, as the carrier 53 is driven by the motor shaft 11, the planet gears 60 roll in an orbit around the then stationary internal gear as a trackway, at the same time revolving on the shafts 55. As the planet gears 60 revolve, the planet gears 61 revolve therewith driving the internal gear 63 which is secured to the feed nut 28'. The friction band 77 may be adjusted by the cam member 85 to slip to vary the rate of rotation of the feed nut. The cam member 85 may be slid over into engagement with any of the other friction bands 14, 75 and 76 to effect different driving speeds through any of the planet gears 57, 58 and 59. It is accordingly evident that the feed nut may be driven selectively at four different forward speeds and any of these speeds may be varied by slipping the friction bands. As in the other embodiment of the invention, suitable reverse gearing may be associated with the planetary gearing to effect reversal of the drive of the feed nut, or feed nut reversal may be effected simply by reversing the motor.

The general mode of the operation of the improved drilling apparatus will be clearly apparent from the description given. When the drilling motor 1 is running and the tubular shaft 11 of the motor armature rotor 10 is rotating, the drilling implement 2 rotates therewith and liquid may be supplied to the drilling implement through the hose connection 15, stuffing box 14 and drill rod. In the embodiment shown in Figs. 1 to 6 inclusive, when the drilling motor 1 is in the position shown in Fig. 1 on the guide 4 and the drilling implement 2 is rotating, the operator may manipulate the hand nut 48 to effect tightening of the friction band 40, thereby frictionally to hold the friction drum 39 against rotation. The feed nut 28 is then driven through the planetary reduction gearing 35, 36, 37 and 38 relative to the stationary feed screw 19 in a direction and at a speed to effect feed of the drilling motor forwardly along the guideways of the guide 4, thereby to move the drilling implement toward the work. The feeding speed may be varied by slipping the friction band 40, and, when the friction band is released, feed may be interrupted while the drilling motor continues to operate. When it is desired to retract the drilling implement from the work, this may be accomplished simply by reversing the motor 1, although, as previously mentioned, a suitable reverse planetary drive may be associated with the planetary reduction gearing to effect rotation of the feed nut in reverse feeding direction without reversing the drilling motor.

In the modified embodiment shown in Figs. 7 to 9 inclusive, the mode of operation of the drilling apparatus is generally similar to that above described. When the drilling motor is running and the motor shaft 11 is rotating, the carrier 53 revolves therewith and when one of the four friction bands 74, 75, 76 and 77 is applied, the feed nut 28' may be rotated through the planet gears, internal gear 63 and rotatable support 64 in a direction and at a speed to effect forward feed. By shifting the cam member 85 into engagement with the desired one of the four friction bands, the desired feeding speed may be selected. By slipping the friction bands, the

rate of feed may be varied, and, by releasing the friction bands, feed may be interrupted during running of the drilling motor. As in the other embodiment, reverse feed may be effected simply by reversing the drilling motor or by operating a suitable reverse planetary drive for the feed nut, associated with the planetary reduction gearing.

As a result of this invention, an improved drilling apparatus is provided whereby a drilling implement may be fed with respect to the work in an improved manner. By means of the improved general arrangement of parts and especially the improved relationship between the feeding mechanism and the other elements, an extremely compact and simplified construction is obtained. By extending the stationary feeding element into the drill rotating shaft in coaxial relation with the drilling motor, not only an extremely compact construction results, but also it is possible to drive the rotatable feeding element directly from the motor shaft of the drill. The novel arrangement of the feeding elements enables improved driving of the rotatable feeding element through driving gearing carried by the drilling tool in an improved manner. Further, the novel arrangement of the feed screw in axial alignment with the drilling tool enables application of feeding forces in direct line with the drill rod and bit, thereby, to a large extent, eliminating undesirable twisting tendencies, resulting in better balance and improved efficiency. Other uses and advantages of the invention will be clearly apparent to those skilled in the art.

While there are in this application specifically described two forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a drilling apparatus, a guide providing a guideway, a drilling motor guided for movement along said guideway and having a rotatable motor element and a tubular shaft coaxial with and driven by said motor element, a connection for a drilling implement secured to the front end of said tubular motor shaft, a feeding element secured at its rear end to said guide against movement relative thereto and extending forwardly into said tubular shaft from a point to the rear of the motor, and a rotatable feeding element at the rear end of said tubular shaft and driven by the latter, said feeding element mounted to move bodily with said motor along said guideway and cooperating with said stationary feeding element, and said rotatable feeding element operating on rotation thereof relative to said stationary feeding element to effect movement of said motor bodily along said guideway to feed the drilling implement toward the work at a drilling speed.

2. In a drilling apparatus, a bodily movable motor for rotating a drilling implement and having a tubular shaft extending axially thereof, a connection for a drilling implement secured to the front end of said shaft, and means for feeding said motor bodily to move the drilling implement toward the work at a drilling speed including a stationary feeding element extending forwardly into said motor shaft from a point to the rear of said motor and a rotatable feeding

element arranged at the rear end of said motor and driven by said tubular shaft, said rotatable feeding element engaging said stationary feeding element and movable forwardly therealong with said motor during feed.

3. In a drilling apparatus, a bodily movable motor for rotating a drilling implement and having a tubular shaft extending axially thereof, a connection for a drilling implement secured to the front end of said motor shaft, and means for feeding said motor to move the rotatable drilling implement toward the work to effect drilling and including a stationary feeding element extending forwardly into said tubular motor shaft from a point to the rear of said motor, and a rotatable feeding element movable forwardly with said motor and engaging said stationary feeding element at the rear end of said motor and movable axially relative to said stationary feeding element during the feeding operation, and variable speed transmission means at the rear end of said motor and movable bodily with the latter for connecting said motor shaft in driving relation with said rotatable feeding element for rotating the latter to effect feed, said transmission means embodying means adjustable for effecting rotation of said rotary feeding element at different speeds.

4. In a drilling apparatus, a bodily movable drilling motor having a rotatable tubular shaft for rotating a drilling implement and said motor and shaft mounted for axial movement with the drilling implement during the drilling operation, a connection for a drilling implement secured at the front end of said motor shaft, and means for bodily feeding said motor to effect axial movement of said shaft and the drilling implement during its rotation to feed the drilling implement toward the work at a drilling speed including a stationary feeding element extending axially into said tubular shaft, a rotatable feeding element arranged at the rear end of said motor and cooperating with said stationary feeding element and moving axially with said motor shaft during feed, and means for driving said rotatable feeding element from the rear end of said tubular shaft at a rotation-speed substantially reduced from the speed of rotation of said motor shaft.

5. In a drilling apparatus, a bodily movable motor for rotating and feeding a drilling implement, a tubular drill spindle coaxial with and driven by said motor, a connection for a drilling implement secured to the front end of said spindle, and means operatively connected to the rear end of said spindle for moving said motor to feed the drilling implement toward the work at a drilling speed during drilling including a stationary feed screw extending forwardly axially into said spindle from a point to the rear of the latter.

6. A drilling apparatus comprising, in combination, a tubular drill spindle, a motor having a rotor coaxial with and fixed to said drill spindle for rotating the latter, a connection for a drilling implement secured to the front end of said spindle a guide having guideways slidably supporting said motor, a feed screw extending forwardly into said drill spindle and fixed at its rear end to said guide against movement relative thereto, a rotatable feed nut mounted to move bodily with said motor along said guideways and operatively engaging said feed screw and having a gear portion, a rotatable reaction gear coaxial with said drill spindle and mounted for bodily move-

ment with said motor, planetary gears carried by said drill spindle and operatively engaging said reaction gear and the gear portion of said feed nut, and adjustable means for variably resisting the rotation of said reaction gear to vary the speed of rotation of said feed nut.

5 7. A drilling apparatus comprising, in combination, a tubular drill spindle, a motor having a rotor coaxial with and fixed to said drill 10 spindle for rotating the latter, a connection for a drilling implement secured to the front end of said spindle, a guide having guideways slidably supporting said motor, a feed screw extending forwardly into said drill spindle and fixed at its rear end to said guide against movement relative thereto, a rotatable feed nut mounted to move bodily with said motor along said guideways and operatively engaging said feed screw and having a gear portion, reaction gears coaxial with said feed nut and supported for rotation relative thereto, planetary gears of different diameters meshing severally with said reaction gears and the gear portion of said feed nut, and adjustable means for selectively and 25 variably resisting the rotation of said reaction gears to vary the speed of rotation of said feed nut.

8 8. A drilling apparatus comprising, in combination, a tubular drill spindle, a motor having 30 a rotor coaxial with said drill spindle for rotating the latter, a connection for a drilling implement secured to the front end of said spindle, a guide having guideways slidably supporting said motor, a feed screw extending forwardly into said drill spindle and at its rear end fixed to said guide against movement relative thereto, a rotatable feed nut operatively engaging said feed screw and mounted to move with said motor, said feed nut arranged coaxial with said spindle at the rear end thereof and having a gear portion, a rotatable reaction gear coaxial with said drill spindle and mounted for bodily movement with said motor, planetary gears carried by said drill spindle and operatively engaging 45 said reaction gear and the gear portion of said feed nut, and adjustable frictional resistance means for variably resisting the rotation of said reaction gear to vary the speed of rotation of said feed nut.

50 9. A drilling apparatus comprising, in combination, a tubular drill spindle, a motor having a rotor coaxial with said drill spindle for rotating the latter, a connection for a drilling implement secured to the front end of said spindle, 55 a guide having guideways slidably supporting said motor, a feed screw extending forwardly into said drill spindle and fixed at its rear end to said guide against movement relative thereto, a rotatable feed nut operatively engaging said feed screw and arranged coaxial with said spindle at the rear end of the latter, said feed nut having a gear portion, reaction gears coaxial with said feed nut and supported for rotation relative thereto, planetary gears of different diameters meshing severally with said reaction gears and the gear portion of said feed nut, and adjustable frictional resistance means for selectively and 65 variably resisting the rotation of said reaction gears to vary the speed of rotation of said feed nut.
